ROTARY TIMER

Filed June 30, 1926

John H. Hobson Inventor

By *Chas. Brown & Co.*
Attorneys

UNITED STATES PATENT OFFICE.

JOHN H. HOBSON, OF SULPHUR SPRINGS, ARKANSAS, ASSIGNOR OF ONE-FIFTH TO J. ALVIN BROWN, ONE-FIFTH TO CHESTER A. SWARENS, ONE-FIFTH TO WILLIAM J. BROWN, AND ONE-FIFTH TO WILSON T. FEAZELL.

ROTARY TIMER.

Application filed June 30, 1926. Serial No. 119,645.

This invention aims to provide a novel means whereby a signal may be sounded at a predetermined time, or when a predetermined pressure has built up, or under any other conditions which may cause a hand to move over a dial.

In the drawings:—

Figure 1 shows in elevation, a device constructed in accordance with the invention; Figure 2 is a fragmental rear elevation showing a portion of the switch mechanism;

Figure 3 is a sectional view taken about on the line 3—3 of Figure 2.

Referring to the drawings, the numeral 1 marks a clock frame within which is located a partition 2, the dial of the clock being designated by the numeral 3 and being provided with an index 30. The minute arbor is shown at 4 and carries the minute hand 5, a hollow shaft 6 being rotatable upon the minute arbor 4, the shaft 6 carrying the hour hand 7.

There is an insulating sleeve 8 on the hollow shaft 6 and about the sleeve 8 is located a tube 9 of conducting material. A binding post 10 is mounted on the partition 2 and carries a conductor 11, the binding post serving as a retainer for a spring brush 12 which rides on the inner end of the conducting tube 9.

The tube 9 has a circumferential rib 14 against which abuts an insulating disk 15 on the tube 9. The disk 15 is frictionally held on the tube 9 to rotate with the tube. By the application of sufficient force, however, the disk 15 may be turned on the tube 9 to adjust the position of the disk. Near to its periphery, the disk 15 is supplied with a plurality of transverse contact buttons 16 provided with fingers 17 which project outwardly to the periphery of the disk 15, the buttons 16 and their fingers 17 being made of conducting material. Spring tongues 18, of conducting material, are mounted on the tube 9 and are held thereon by a nut 19 threaded on the tube 9, the nut binding the tongues 18 against the circumferential rib 14. The construction is such that the tongues 18 ordinarily move with the disk 15 when the disk 15 turns with the tube 9, but it is possible to swing any of the tongues 18 with respect to the disk 15, so as to place the outer ends of the tongues 18 on any desired ones of the

contact buttons 16, the buttons being numbered from one to twelve, to correspond with the hours of the day.

A radius arm 20 is provided, and is pivotally mounted at 21 on the partition 2. Near to its free end, the radius arm 20 carries an insulating bushing 23. In the bushing 23 is mounted a contact and binding member 24. The inner end of the contact and binding member 24 rests on the periphery of the disk 15 and is adapted to come into contact with the buttons 16, as the disk 15 is rotated. In order to secure a firm contact between the member 24 and the buttons 16, the radius arm 20 is drawn downwardly by a retractile spring 22, the upper end of the spring being connected to the radius arm 20, and the lower end of the spring being connected to the partition 2, as disclosed in Figure 2. A conductor 25 is joined to the contact and binding member 24 and extends through a hole 26 in the partition 2.

The operator fixes upon the hour when he wishes the alarm to be sounded, and sets the tongues 18, accordingly, on the contact buttons 16. If it is desired that the alarm shall be sounded on the half hour, or at any time between the even hours, then the disk 15 is turned forcibly on the shaft 6, the index 30 being made use of to set the disk 15 in such a way that the alarm will be sounded on the half hour, or at any other time between the hours—an observation which will be understood readily when Figure 1 of the drawings is noted.

The disk 15 rotates with the hour shaft 6, and, ultimately, that one of the contact buttons 16 whereon the tongue 18 rests, comes up into contact with the member 24 on the radius arm 20. When there is established a circuit comprising the conductor 11, the spring brush 12, the conducting tube 9, the spring tongue 18, the contact button 16, and its finger 17, the contact member 24 on the lever 20, and the conductor 25, it being possible, thus, to sound or operate otherwise a signal (not shown) located in a circuit whereof the conductors 25 and 11 form parts.

What is claimed is:—

In a device of the class described, a frame, a shaft extended through the frame, an insulating sleeve on the shaft, a conducting

tube about the sleeve, a binding post on one side of the frame and having means for holding a conductor, a brush retained by the binding post and riding on one end 5 of the conducting tube, an insulating disk frictionally held on the tube and located on the opposite side of the frame, the disk being provided with side contacts which are exposed at the periphery of the disk, the 10 tube being provided with a circumferential rib against which the disk abuts, a spring

tongue, means for binding the tongue adjustably against the rib, whereby the tongue may be shifted to engage any of the contacts, yieldable mechanism for engaging 15 any of the contacts at the periphery of the disk, and means for bringing said mechanism into an electrical circuit.

In testimony that I claim the foregoing as my own, I have hereto affixed my signature.

JOHN H. HOBSON.
